UNITED STATES PATENT OFFICE

2,538,184

ELECTRONIC PIANO TUNING

Clifford Andersen, De Kalb, Ill., assignor to The
Rudolph Wurlitzer Company, De Kalb, Ill.

Application August 7, 1946, Serial No. 688,897

4 Claims. (Cl. 84—454)

1

This invention relates to piano tuning, and particularly to an electrical pick up mechanism in an electronic circuit such as to amplify the sound waves developed from a selected piano string over and above those of its associated unison of strings.

Wherein piano strings are arranged in a unison of two or three strings for each note, it has been customary in tuning each string of the unison to dampen out the other strings by applying thereto rubber wedges, felt, or the like. This is necessary in order that the sound vibrations of the string being tuned will not be interfered with by those of its associated strings.

It is the object of this invention to eliminate the necessity of dampening out the associated strings by amplifying the sound waves of the string being tuned to distinguish it therefrom. This is accomplished by conveniently applying to such string being tuned a pick up mechanism for electrically transmitting the vibrations thereof to an audio amplifying circuit for sound amplification.

The full nature of the invention will be understood from the accompanying drawings and the following description and claims:

Fig. 1 is a perspective view of the pick up mechanism.

Fig. 2 is a plan view of the pick up mechanism with its housing shown in section.

Fig. 3 is the same as Fig. 1 showing a side elevation thereof.

Fig. 4 is the same as Fig. 3 showing a modified form of pick up mechanism.

In the drawings there is shown an electronic piano tuning device comprising an elongated metal vibration transmitting element herein illustrated as a rigid bar 10, to one end of which there is rigidly connected a spring clip 11 for conveniently contacting one of the unison of piano strings 12.

The vibration bar 10 is rigidly connected at its other end to the electrical vibration transmitting pick up mechanism 13 such as the usual commercial phonograph pick up, well known in the art. In place of the usual pick up needle or stylus, the pick up 13 is rigidly connected with that end of the bar 10 opposed to the string engaging clip 11 by the screw 14. Thus the screw 14 is inserted in the pick up 13 in the manner of a phonograph needle but is so formed as to be firmly fixed to the end of the bar 10. As herein shown it is threaded to be screwed therein. The pick up 13 is electrically connected through a cable 15 to an electronic amplifier

2

16, and frequency comparing and measuring unit 17. The pick up 13 is preferably encased for handling within the housing 18 containing a felt wrapping or packing 19.

5 The frequency comparing and measuring unit 17 may be of various known types, one type comprising a cathode ray tube with one set of deflection plates connected to the pick up through the audio amplifier 16, and the other set of deflection plates to any well known and suitable audio frequency standard, not shown herein. The latter deflection plates may be fed by a controlled saw tooth wave oscillator to indicate flat or sharp as well as resonance. Another well known type of frequency comparing and measuring unit is that known as the "Stroboscope" manufactured by C. G. Conn, Ltd., of Elkhart, Indiana. By the use of this invention there is developed a higher signal to noise ratio resulting in a much better and clearer image seen on the frequency and measuring unit 17. The invention also eliminates the use of rubber wedges and felts such as are necessary when using the usual microphone pick up.

25 In tuning the unison of strings 12 shown herein as comprising three piano strings, the clip 11 is engaged over the particular string to be selectively tuned. The string is contacted preferably between the upper bearing and the pressure bar, since if it is engaged at the striking point the pitch thereof may be slightly changed. The unison of strings is then struck by the action hammer and although the other strings of the unison may be sounded as usual there will be sufficient amplification of the selected string being tuned transmitted through the pick up and electronic circuit to distinguish its frequency from that of the other strings of its unison.

30 In the modified form of the electronic tuning device the vibration bar 110 is connected to the electric pick up mechanism 113 through a small diameter rod 114 which is rigidly set in the bar to extend upwardly therefrom and be clamped in the pick up by the usual clamp screw 115.

45 The opposite end of the pick up may be removably secured to and supported upon the end of the bar 110 by an anchor pin 116. Preferably the pick up and the portion of the bar to which it is anchored is wrapped in felt and encased by a housing as above described.

50 Whereas the vibration bars 10 and 110 have been shown herein as of varying lengths they may also be formed to any desired curvature or bent at any angle for convenient application to the piano string. Similarly, a flexible steel cable

may be employed to transmit the vibrations from the string to the pick up where desired, although it is found that the use of such a cable causes a slight dampening of the amplitude of the vibration. The pick up mechanism may be of the usual crystal type or of the magnetic type to receive and electrically transmit in the usual manner thereof vibrations from the bars 10, 110 through the phonograph needle like connecting rods 14, 114, respectively.

The invention claimed is:

1. An electronic device for tuning piano strings upon manual vibration thereof comprising a mechanical vibration transmitting element, the receiving end of which is adapted to be selectively placed in direct contact with a selected string to be tuned, an audio amplifying circuit, and an electrical vibration transmitting pick up mechanism connected at one end thereof to the other end of said vibration transmitting element and having its output end connected in said circuit for electrically transmitting mechanical vibrations of the selected string to said audio amplifying circuit.

2. An electronic device for tuning piano strings upon manual vibration thereof comprising a mechanical vibration transmitting element, a spring contact clip secured to the vibration receiving end of said element for connecting it in direct contact with a selected string to be tuned, an audio amplifying circuit, a frequency comparing and measuring unit connected therewith and an electrical vibration transmitting pick up mechanism having a vibrating member rigidly connected with the other end of said vibration transmitting element to mechanically transmit vibration from the manually vibrated string to said mechanism, said pick up mechanism having its output end electrically connected in said amplifying circuit.

3. An electronic device for tuning piano strings upon manual vibration thereof comprising a mechanical vibration transmitting element, the receiving end of which is adapted to be selectively placed in direct contact with the selected string to be tuned, an audio amplifying circuit, a frequency comparing and measuring unit connected with the output end of said circuit, and an electrical vibration transmitting pick up mechanism connected at its in-put end to the other end of said mechanical vibration transmitting element and having its output end connected to the input end of said circuit for electrically transmitting vibrations of the selected string into said circuit for frequency measurement and comparison.

4. The method of tuning a selected one of a unison of piano strings, consisting in selectively and directly engaging the selected string with an electronic pick up device for receiving mechanical vibrations therefrom, simultaneously striking all strings of the unison, and electrically amplifying the transmitted mechanical vibrations of the selected string of the unison for electronic frequency comparison and measurement thereof.
